(57) **CLAIM**

The ornamental design for a high product density interactive rotating kiosk, as shown and described.

DESCRIPTION

FIG. 1 is a top view of a high product density interactive rotating kiosk showing the new design;

FIG. 2 is a front elevational view of the high product density interactive rotating kiosk shown in FIG. 1 (the rear elevational view of the high product density interactive rotating kiosk is a mirror image of the view shown in FIG. 2 except with several parts rearranged on either side as shown in FIG. 3);

FIG. 3 is a left side elevational view of the high product density interactive rotating kiosk shown in FIG. 1 (the right side elevational view of the high product density interactive rotating kiosk is a mirror image of the view shown in FIG. 3 except with several parts rearranged on either side as shown); and,

FIG. 4 is a perspective view of the high product density interactive rotating kiosk shown in FIG. 1.

Applicants specifically disclaim any surface ornamentation, logos, written matter, kiosk attachments and/or extensions therefrom such as but not limited to keyboards, display holders and backboards, rotatable wheels, wheel tabs, filters, ports, caps, attachment ports and/or bases, grooves, ribs, or any other features apart from the primary outer surface, all of which form no part of the claimed design.
